UNITED STATES PATENT OFFICE.

VOJTECH PUC, OF PRAGUE-VINOHRADY, BOHEMIA.

MACHINE FOR FEEDING ARTICLES TO CARDING AND OTHER MACHINES.

Application filed February 3, 1920. Serial No. 355,977.

(GRANTED UNDER THE PROVISIONS OF THE ACT OF MARCH 3, 1921, 41 STAT. L. 1313.)

To all whom it may concern:

Be it known that I, VOJTECH Puc, a citizen of the Republic of Czechoslovakia, residing at Prague-Vinoohrady, in Bohemia, have invented certain new and useful Improvements in Machines for Feeding Articles to Carding and Other Machines (for which I have filed applications in Austria, filed Aug 1, 1913, patented July 10, 1914, 10 No. 65,473 in France, filed July 25, 1914, patented June 17, 1915, No. 476,951), of which the following is a specification.

This invention relates to machines for feeding articles to carding and other machines, and particularly to machines for feeding members of snap fasteners or press buttons to machines for fastening them to cards.

Heretofore machines for this purpose have been constructed to apply stud and socket members of the fasteners to opposite sides of perforated cards, the studs being passed through the perforations in the cards and made to engage the socket members by suitably constructed punches. The two sets of fastener members have heretofore been supplied to the cards through a plurality of troughs or channels, there being as many troughs or channels as there are fasteners 30 to be applied in a row to a single card. These supply troughs or channels have been positioned either directly above the path of a slide, or else discharge into conveyers which carry the articles directly into the 35 range of the punches.

According to my invention, the feed mechanism is materially simplified. In carrying out my invention, the articles are conveyed in regular order through a trough 40 or feed channel to a carrier which receives a predetermined number of articles and then moves to a position over a table where it deposits the articles in front of a reciprocating slide which is so shaped as to pick up the articles, arrange them in the desired order and shape, and convey them to the cards to which they are to be attached. The mechanism is automatic in operation, first receiving the proper number of articles 45 from the feed trough, then carrying them to the table and at the same time cutting off the supply from the trough, then depositing the articles on the table, and then returning to the feed trough, opening it, and re-

ceiving another supply of articles. The action of the slide is entirely automatic, as it picks up the articles from the table, arranges them in proper order and shape, and carries them to the card in proper relation to the punches.

I have shown my invention as applied to a machine for feeding the socket member of snap buttons, but it must be understood that some features of my invention may be embodied in machines for feeding and applying other articles.

In the accompanying drawings:

Figure 1 shows a side elevation of so much of a machine for feeding and applying snap buttons to cards as is necessary to illustrate my invention.

Figure 2 is a top plan view of the mechanism shown in Figure 1.

Figure 3 is a perspective view, showing the mechanism in position to deposit the articles on the table in front of the slide.

Figure 4 shows a section on the line 4—4 of Figure 2 and illustrates how the buttons are held in the carrier and how they may be discharged therefrom onto the table.

Figure 5 is a plan view showing the articles engaged by the slide and carried forward to a card and in position to be acted on by punches.

Figures 6 to 10, inclusive, show a modified form of the invention, in which the carrier is made to reciprocate in a straight line instead of being swung on a pivot in the manner indicated in Figures 1 to 5.

Figure 6 is a plan view of the mechanism.

Figure 7 is a detail view in section on the line 7—7 of Figure 6.

Figure 8 shows an end elevation of the mechanism.

Figure 9 is a detail view in section on the line 9—9 of Figure 6.

Figure 10 is a detail view in section on the line 10—10 of Figure 6.

Referring to Figures 1 to 5, inclusive, the table to which the snap buttons are delivered and on which the slide moves is indicated at A, and B indicates the slide which is reciprocated on the table by any suitable mechanism. The slide is formed at its front end with teeth b between which there are curved, elongated recesses b'. The ends of the teeth are pointed, and the recesses are so shaped and are of such length that when

the teeth fully engage the buttons, the latter will be held in the desired arrangement. In the particular form of the slide shown, the teeth are adapted to engage two sets of buttons and to cause them to be arranged in two semi-circles, but this arrangement is not essential.

As shown in Figure 4, the teeth *b* are relatively thin, providing a space *x* beneath them, the arrangement being such that the bodies of the buttons *X* enter the space *x* while the upper parts, caps or socket portions of the buttons enter the recesses *b'*. The articles operated upon are indicated at *X*, in this instance being socket members of snap buttons of the usual kind. The card to which the buttons are applied is indicated at *Y*. Figure 2 shows the slide in its retracted position, but ready to move forward and engage the row of buttons deposited on the table by the carrier, presently to be described. Figure 5 shows the slide moved forward with the buttons properly arranged in the recesses *b'* at the front end and with the slide and buttons in position over a card and with the buttons ready to be acted on by the punches to connect the socket members with the stud members of the buttons.

C indicates a feed trough or channel by which the buttons are conveyed from a machine which supplies them in regular order and in proper arrangement so that they may be delivered in a row with their caps uppermost, in the manner indicated in Figure 2. The carrier which transfers the buttons from the feed trough to the table is indicated, generally, by the letter *D*. The carrier *D* comprises a bar *E* pivotally connected with a support *F* at *f*. The pivot for the bar is arranged at an angle of 45° with reference to the horizontal plane of the table *A*. The lower portion of the bar *E* projects beyond the pivot and is connected with a rod *G*, by means of which the carrier is swung about the axis of the pivot in such manner that it will move from the position shown in Figure 2, in line with the feed trough, to the position shown in Figure 3, across the operating table. The bar *E* has secured to it a bar *H* which is undercut at *h* (Fig. 4) to receive a portion of the body of the buttons *X*. The bar *E* has also secured to it a bar *K* formed with a series of teeth *k* with intervening recesses *k'*. There is a space *M* between the inner edges of the bars *H* and *K*, and in this space operates a gate or holder *L*, which as shown by dotted lines in Figure 4 engages the buttons and prevents them from dropping out of the carrier. The gate is carried by two arms *l* secured to a rod *l'* supported in a bifurcated frame *l''* secured to the bar *H*. A spring *n* on the rod *l'* has a projection *n'* which bears on the gate and tends to hold it in its lower position as indicated by dotted lines (Fig.

4). When in its lowermost position the gate prevents the buttons from leaving the carrier. The rod *l'* carries on one end an arm *o* which is adapted to engage with an arm *p* of a bracket *P* secured to the table *A*. *Q* indicates a gate for closing the mouth of the feed trough when the carrier is moved away from it.

The gate has an arm *q* which is guided by a bracket *q'* and is normally pressed inwards by a spring *q''*. The gate is formed with an arm *q''* which is adapted to engage the bar *H*. When the carrier is in position in line with the feed trough, the bar *H* engages the arm *q''* of the gate and holds it open so that buttons may pass from the trough into the carrier, but as soon as the carrier leaves the trough, the gate closes the mouth of the trough so that no buttons may pass therefrom. When the gate is open, buttons pass from the feed trough into the space *M* in the carrier, the lowermost button resting against the stop *m*. At this time the gate *L* is lowered as indicated by dotted lines in Figure 4. When the carrier is filled or has received the proper number of buttons, it is swung from the position shown in Figure 2 to that shown by full lines in Figure 3, the arm *o* being engaged by the bracket *P* and the gate *L* is lifted. The buttons then pass from the carrier onto the table and are disposed in a row transversely across the table as shown. The carrier is returned to the feed trough and the slide moves forward from the position shown in Figure 2 to that shown in Figure 5, operating in the manner before described. When the carrier comes opposite the feed trough it engages the arm *q''* of the gate, which is thus opened and the proper number of buttons pass from the feed trough into the carrier, and the operation then proceeds in the manner before explained.

It will thus be seen that I have very materially simplified the mechanism for carrying buttons from a feed trough to a position on a table where they are operated upon by other mechanism, having dispensed with the multiplicity of feed troughs heretofore used, a single device being employed to transfer the desired number of articles from a source of supply to a point of delivery. The results above explained may be obtained in modified forms of machines. I have shown in Figs. 6 to 10, inclusive, mechanism in which the carrier is reciprocated in a straight line instead of being swung on an inclined pivot.

Portions of a suitable supporting frame are inclined at *R*, and on a downwardly inclined projecting part *r'* of the standard *r* of the frame, the feed trough *S* is supported. This trough, as shown, comprises a bar *s* inclined from its upper end downwards and secured to the frame part *r'* and two parallel bars *s'* which are spaced apart and secured

to the bar s by screws s^2 , passing through collars or washers s^3 . In this way a guide channel is produced for the buttons, which are supplied in any suitable way to the 5 top of the trough and pass down the channel Z indicated in Figure 7.

T indicates a carrier which is mounted to reciprocate in a straight line and in a horizontal plane across the lower end of the feed 10 trough.

The carrier is supported by the standard r^2 rising from the frame R. This standard also supports a work table U on which reciprocates a slide U' similar in form and operation to that shown and described in connection with Figures 1 to 5, inclusive. The carrier comprises a lower bar V and an upper bar W. The lower bar V is supported by the standard r^2 and is adapted to reciprocate in guides therein. It is actuated by a rod v suitably connected at v' with it. The bar W is connected to the bar V by screws w which extend through holes in the bar W and screw into the bar V. Springs w' between the heads of the screws and the top of the bar W yieldingly hold the latter bar in the position shown in Figure 9 against the collars or washers v^2 .

The upper bar W is formed with a series 30 of teeth w^2 with recesses w^3 between them to receive the buttons from the feed trough S. The upper bar W is also formed with a gate g which serves to close the mouth of the channel or feed trough when the carrier 35 is moved to its outermost position. At the proper time the upper bar W is raised to permit the buttons to slide over the lower bar V (Fig. 9) onto the table U (Fig. 8). In order to do this I may employ the mechanism shown. 1 indicates a rock shaft which may be actuated by any suitable mechanism 40 2, and on the shaft is mounted an arm 3, to which is secured by screws 4 a plate 5 which projects beyond the lower end of the arm. 45 The plate may be adjusted longitudinally on the arm by the screws which pass through slots 6 in the arm and screw into the plate. The lower end of the plate is formed with a finger 7, which engages a roller 8 carried in 50 a frame 9 secured to the upper bar W. The arm 3 with the plate 5 slides on the shaft 1 and moves coincidentally with the carrier, but is adapted to rock at the proper time with the shaft when the latter is actuated.

55 Figure 6 shows by dotted lines the position of the mechanism when the carrier has reached the limit of its outward movement and by full lines the position of the carrier when it has just commenced its inward movement. When the carrier is at the limit of its outward movement, the gate g closes the mouth of the feed trough. As soon as the carrier commences to move inward, the mouth of the feed trough is opened and the 60 buttons are delivered one by one to the re-

cesses w^3 in the upper bar W. The carrier continues its inward movement until the last recess w^3 is opposite the lower end of the feed trough and by this time all the recesses are filled. The carrier is then moved outward and when it reaches the limit of its outward movement, the shaft 1 is rocked and the upper bar is lifted (Fig. 9), and all the buttons are simultaneously deposited on the table. Immediately after this, the bar 70 75 W is lowered and the carrier returns to its initial position, while doing so taking up a new supply of buttons.

It will thus be understood that my improvements may be embodied in machines 80 differing somewhat in construction and operation. I have illustrated one machine in which the carrier is pivoted to move about an inclined axis, and another machine in which the carrier is mounted to reciprocate 85 in a straight line. Other modifications might be illustrated, but the machines shown embody the principle of my invention and are the best ways now known to me of using it. 90

I claim as my invention:—

1. A machine for feeding articles from a source of supply to other machines, comprising a recessed carrier which receives a plurality of articles from the source of supply, 95 means for feeding the articles to the carrier, means for holding the articles in the carrier, means for moving the carrier from the source of supply to the point of delivery, and means operated by the movement of the 100 carrier for releasing the articles from the carrier.

2. A machine for feeding articles from a source of supply to other machines, comprising a recessed carrier which receives a plurality of articles from the source of supply, 105 means for feeding the articles to the carrier, means for holding the articles in the carrier, means for swinging the carrier about an inclined axis from the source of supply to the 110 point of delivery, and means for releasing the articles from the carrier.

3. A machine for feeding button members from a source of supply to other machines, comprising a recessed carrier which receives 115 a plurality of said members one after another from the source of supply and holds them in a straight row along the carrier, means for feeding said members to the carrier, means for swinging said carrier about an external axis to a horizontal position at the point of delivery, and means for releasing the members from the carrier. 120

4. A machine for feeding buttons from a source of supply to other machines, comprising a recessed carrier having a channel or space into which the buttons pass from the source of supply and provided with recesses through which the buttons are delivered, a 125 gate for holding the buttons in the carrier, 130

- a gate for closing the source of supply, means for moving the carrier from the source of supply to the point of delivery, means for opening the gate of the carrier to release the buttons, and means operated by the carrier for opening and closing the mouth of the source of button supply. 5
5. A machine for feeding articles from a source of supply to other machines, comprising a recessed carrier which receives a plurality of buttons from the source of supply, means for holding the buttons in the carrier, means for moving the carrier from the source of supply to the point of delivery, 10 means for releasing the articles from the carrier, and a recessed slide which engages the articles thus delivered, arranges them in proper order, and carries them to other mechanism. 15
6. A machine for feeding articles from a source of supply to other machines, comprising a carrier having a space to receive the articles and transversely arranged recesses through which articles are delivered, a 20 spring actuated gate for holding the articles in the carrier, means for moving the carrier from the source of supply to the point of delivery, means for opening the gate to deliver the articles from the carrier, and means operated by the carrier for opening and closing the mouth of the source of supply. 25
7. A machine for feeding articles from a source of supply to other machines, comprising an inclined carrier into which the articles feed from the source of supply by their own weight, one after another, means for swinging the carrier from the source of sup- 30
- ply to a horizontal position at the point of delivery, and means for releasing the articles from the carrier. 40
8. A machine for feeding articles from a source of supply to other machines comprising an inclined carrier into which the articles feed from the source of supply by their own weight one after another, means for holding the articles in the carrier, means for swinging the carrier from the source of supply to a position at the point of delivery in which the articles are arranged in a horizontal row, and means for releasing the articles 45 from the machine. 50
9. A machine for feeding articles from a source of supply to other machines comprising an inclined carrier into which a predetermined number of articles are fed from the source of supply, one after another, means for holding the articles in said carrier, means for swinging the carrier from the source of supply to the point of delivery, and means for releasing the articles simultaneously in a horizontal row. 55
10. A machine for feeding articles from a source of supply to other machines comprising a carrier mounted in an inclined position and receiving articles one after another from a source of supply, means for holding the articles in the carrier, means for swinging the carrier about an external axis to a horizontal position at the point of delivery, and means for releasing the articles simultaneously. 60

In testimony whereof, I have hereunto subscribed my name.

VOJTECH PUC.
